ATTORNEY

UNITED STATES PATENT OFFICE.

ALLEN A. RUSSELL, OF INDIANAPOLIS, INDIANA, ASSIGNOR TO RUSSELL & COMPANY, OF MASSILLON, OHIO.

STRAW-STACKER.

SPECIFICATION forming part of Letters Patent No. 400,798, dated April 2, 1889.

Application filed June 6, 1888. Serial No. 276,268. (No model.)

To all whom it may concern:

Be it known that I, ALLEN A. RUSSELL, a citizen of the United States, and a resident of Indianapolis, county of Marion, State of Indiana, have invented a new and useful Improvement in Straw-Stackers, of which the following is a full, clear, and exact description, reference being had to the accompanying drawings, making part of this specification.

10 My invention relates to improvements in straw-stackers, and especially to that class of stackers mounted on trucks, and in operation may be automatically oscillated horizontally about its pivotal connection with the supporting truck or frame, or may be oscillated manually and folded together and down for convenience and safety in transportation.

With these ends in view my invention consists of the detail and combination of parts, 20 as described, and set forth in the claims.

Figure 1 is a side elevation of a straw-stack and truck, showing the parts in normal position, the folding portion of the stacker disconnected and shown separately for the 25 purpose of convenience. Fig. 2 is a like view showing the stacker folded together and down upon the truck for transportation. Fig. 3 is an isometrical view of stacker-supporting frame and devices by which the stacker and 30 folding frame may be operated. Fig. 4 is a front elevation showing the truck-frame, folding and oscillating frames, and devices for operating the same. Fig. 5 is a view of an apron-supporting pulley. Fig. 6 is a view of a friction shoe by which the movement of the 35 stacker may be regulated. Fig. 7 is a perspective of an oscillating journal-box. Fig. 8 is a view of clutch and hoisting-pulley, and Fig. 9 is a gear-shipper.

40 Similar letters of reference indicate corresponding parts in all of the figures of the drawings.

A represents the axle of the truck; B, the carrying-wheels; C, the bolster; D, the sills; 45 a the rear and a' the front standards.

a² is a strut connecting the sills D' at their front end. A similar strut (not shown in the drawings) connects the rear ends of the sills.

To the sills D' vertical posts, as a³, are 50 secured, as shown, supported by braces a⁴.

A cross-shaft, E, is supported in journal-boxes a⁵, on the inner end of which there are provided inwardly-projecting sleeves a⁶. On the shaft E the uprights F' of the frame F are loosely mounted, and about which said frame 55 may be rotated for the purpose of folding it down upon the standard a' for transportation or raised vertically to support the stacker when operated, and when so raised may be secured to the post a³. The cross-shaft E is also 60 supported by arms a⁷, projecting downwardly from the sill G, the lower ends of said arms embracing the shaft, as shown in Fig. 3.

On shaft E and centrally thereto is mounted a spool, as a⁸, and on the ends thereof spools a⁹, said latter spools engaging a notched or serrated hub, b, and is held in such engagement by a thumb-nut, b'. There is also provided on said shaft a worm-wheel, b², that is rotated by a worm, b³, on shaft b⁴ in housing 70 b⁵, and on the outer end of said shaft is provided an actuating-crank, b⁶. A cable, as H, is wound about the pulleys a⁹, one end of which is run over a sheave, b⁷, secured to the sill D, the other over a similar sheave, b⁸, secured to the upper portion of the post a³, and both ends secured to the uprights F' of the frame F, substantially as shown in the drawings. 75

The folding frame F is composed of the vertical end pieces, F', a strut, d, sill d', and vertical supports d², d³, and d⁴. The stacker-actuating shaft J is supported by a journal-box, d⁵, and hanger d⁶. On the outer end of said shaft is mounted a pulley, d⁷, for a belt 85 engagement with a similar pulley on the thrasher, by which the shaft is rotated, and on the inner end a driving-pinion, d⁸. In the strut d is provided a suitable journal-box, d⁹, for the support of the vertical shaft K. 90

To provide space between the sill d' and bolster L, a block, as f', is secured to said sill, upon which is secured a circular way or plate, M, having a central and upwardly-projected thimble, that forms a journal-box and support for the upper end of shaft K and a spindle-support for the turn-table N, to which the bolster L is secured. The shaft K is passed through the journal-boxes referred to, and on its lower end is mounted a bevel-wheel, f², en- 95

gaging the driving-pinion d^8 , and on the upper end of said shaft is mounted a pinion, f^3 , which engages a similar pinion, f^4 , on shaft O. The inner end of said shaft is supported 5 in a journal-box, f^5 , secured to the bolster L, the outer end in a journal-box, f^6 , having an inwardly-projected shell, f^7 . On the outer end of said shaft is mounted a sprocket-wheel, P, hereinafter explained. Shaft K is further 10 provided with pinions f^8 and f^9 , loosely mounted thereon at a suitable distance apart to engage with a bevel-wheel, g, mounted on shaft Q.

On the inner ends of the hubs of pinions 15 f^8 and f^9 there are provided rack-teeth g^1 and g^2 . Between said teeth a sliding clutch, h^{10} , is secured to the shaft in the usual way of securing such parts, said clutch having teeth g^3 at each of its ends adapted to alternately engage 20 the rack-teeth g^1 and g^2 . An annular groove, g^4 , is provided about said clutch, in which is placed the prongs of the shipper g^5 . (See Figs. 3 and 4.) The outer end of said shipper is secured to a rock-shaft, g^6 , which 25 rocks in bearing in pedestal g^7 .

A short arm having a T-head, g^8 , with pins, as g^9 , in its ends, as shown in Fig. 3, is secured to the rock-shaft g^6 , and a vibrating lever, h, is loosely secured to said shaft, having 30 on its free end a weight, as h^1 . To secure an engagement of the clutches, the shipping devices hereinbefore named having disengaged the clutch from one of the pinions f^8 or f^9 , the weight will operate to move the 35 clutch into engagement with the other. The lever vibrating between the pins g^9 will, when it has passed the vertical line, fall either way against the pins and carry the clutch home. To said lever there is pivotally secured a link, 40 h^2 , connecting said lever to a trip-rod, h^3 , said rod being secured to the frame F, substantially as shown, the operation of which will be hereinafter explained.

Shaft Q, hereinbefore referred to, is supported 45 at its inner end in a journal-box, h^4 , pivotally secured to a supporting-hanger, h^5 , secured to support d^3 , as shown in Fig. 4, the other end supported in a sliding journal-box, h^6 , on support d^4 .

There is provided on said shaft a worm, h^7 , that engages wheel h^8 on shaft R, said shaft rotating in journal-boxes h^9 . Secured to the frame F on the upper end of said shaft is mounted a spur or face pinion, k. (See Fig. 53.) A shipping-lever, S, is provided having one of its ends pivotally secured to support d^4 , as shown at h^1 , Fig. 9, and on its free end a weight, as h^2 , and near its pivoted end a slot, h^3 , to embrace the shaft Q; and to the 60 free end of the lever S a cord, h^4 , is secured and passed up and along the stacker to the outer end, at which point it may be secured, by which the lever S is held in position to secure an engagement of the worm h with the 65 wheel h^8 , which will be hereinafter explained.

The turn-table N is provided with a loop, h^{10} , to embrace the outer edge of the plate M.

In said loop is placed a friction-shoe, k^5 , which may be adjusted by the thumb-screw k^6 . Said table is also provided with radial arms k^7 , supporting a rig, k^8 , having perforations k^9 , and a segment, T, having internal teeth, m, that engage the teeth of pinion k.

The stacker-frame Z is pivotally secured to the bolster L, about the sleeve f^7 of journal-box f^6 , and a corresponding stud-pin, m, the inner section of which frame is composed of side girts, U, supported by a truss, m' , substantially as shown in Fig. 1. The outer ends of the girt U and truss m' are secured to the hinge-plate m^2 , the inner ends to arms m^3 . The outer section is formed of girts m^4 , both sections being provided with side boards, m^5 , and are folded in the usual way, and at each end of the stacker there is provided rollers 85 m^6 and m^7 , of the usual form for such purposes, about which is placed an endless apron or belt, m^8 , composed of endless bands and cross-slats, as is usual in the construction of straw-stackers. The upper or carrying part 90 of said apron in its outward movement is supported on the floor of the stacker-frame. The lower part is supported on carrying-wheels n, having a series of peripheral recesses, as n' , adapted to receive the cross-slats n^2 , the belt 95 resting on the peripheral surface of the wheel. By this arrangement the apron may be run close to the bottom of the stacker-frame, where its movements will not be interrupted by the wind, as is now the case with such aprons 100 when allowed to sag down in the usual way.

A lever, W, is provided having its rear end, n^3 , secured to a strut secured to the truss m' , the front end resting on journal-box f^5 on bolster L, near the front end of the stacker, 105 (free from the stacker-frame,) by which the stacker may be raised and held in desired adjustment without strain on the front end of the stacker or liability to cramp or bind the working parts.

To the front end of lever W there is secured a single tackle-block, n^4 . A corresponding block is secured to a frame, X. Through the said blocks a single rope, n^6 , is rove, one end of which is attached to the frame X by a hook, as n^7 , the other end to spool a^8 on shaft E, about which it may be wound, as herein-after explained. On the end of roller-shaft m^7 is mounted a sprocket-wheel, n^8 , about which is placed a sprocket-chain, n^9 , engaging said wheel to a similar wheel, P, on shaft O, by which the endless apron m^8 is operated. For convenience when moving the machine the frame X may be swung back and up, as shown in Fig. 2.

The operation is as follows: Beginning with machine in position as shown in Fig. 2, the end section may be unfolded or turned back into working position. To raise the machine into position shown in Fig. 1 the crank b^6 is turned, by which the shaft E is rotated, and with it the spools a^9 , about which the lifting-cable H is secured. When the frame F has been raised to a vertical position, (shown in

Fig. 1,) the thumb-screws b' are turned off a distance, releasing the spool from the notched hub b , and by again turning the crank b^6 to rotate shaft E rope n^6 will be wound about 5 spool a^8 to draw the lever W down, as shown in Fig. 1, to elevate the outer or rear end of stacker, as shown in same figure. This movement may be varied to adapt the machine to its work.

10 By the driving-belt, hereinbefore referred to, rotating actuating-shaft J , which, by means of shafts K and O , geared as shown in Fig. 4, and the chain engagement of the sprocket-wheels P and n^8 , the endless apron 15 m^8 is operated for the purpose of carrying the thrashed straw from the thrashing-machine to the stack.

To oscillate the stacker automatically and continuously about its pivotal connection 20 with the supporting-bolster or oscillating frame L , the wheels $f^8 f^9$, engaging wheel g on shaft Q , rotate worm h^7 , engaging wheel h^8 , by which shaft R and pinion k are rotated, 25 said pinion engaging the teeth m of segment T to rotate the turn-table N , which movement is reversed by placing pins p (see Fig. 4) in the perforations k^9 in ring k^8 , one on each side of the cranked end q of the trip-rod h^3 . (See Fig. 4.) The pinion k , rotating the turn-table 30 N , will bring the pins p in contact with the horizontal portion q of the trip-rod, and rotate said rod a distance, which by its linked connection with lever h will rock the shaft g^6 , and gear-shipper g^5 will vibrate the clutch h^10 , 35 engaging and disengaging the teeth of the clutch with the teeth g' and g^2 of f^8 and f^9 , by which the movement of the wheel g and worm h^7 is reversed, thereby reversing the movement of shaft R , pinion k , and turn-table N , bolster L , and stacker.

The extent of oscillation may be regulated 40 by the pins p and perforations k^9 , and to arrest the oscillation of the stacker the shipping-lever S may be brought into action to 45 throw the worm k^7 out of engagement with the wheel h^8 . This may be done from the stack by use of the cord k^4 , after which the stacker may be oscillated manually and allowed to remain in the various positions of 50 use any desired length of time, the oscillations being under control of the operator from the stack.

The advantage of thus being able to control the movement of the stacker by the operators on the stack who have the stacker 55 constantly under observation will be apparent not only to prevent the destruction of the stacker, but to enable them to have the straw deposited at any given point for a given 60 length of time, and be again thrown into operation at the will of the operators, as occasion may require.

Having thus fully described the nature and object of my invention, what I claim as new, 65 and desire to secure by Letters Patent, is—

1. A stacker supporting and carrying truck comprising the carrying-wheels B , axles A , a

bolster, C , pivotally secured to the front axle, standards a , secured to the rear axle, standards a' , secured to the bolster, sills D' , secured to the standards $a a'$ at a point above the said bolster and rear axle, as shown, and vertical posts a^3 , rigidly secured to the sills D as a support for the folding frame F , substantially as described, and for the purpose 75 set forth.

2. The combination, with the supporting-frame, of a cross-shaft, E , extending through the said frame, having spools on the ends thereof, a vertical post secured to said frame, 80 a folding frame, F , pivotally secured about said shaft, a pulley secured at the upper portion of said vertical post, a similar pulley secured to the supporting-frame, a cable wound about the spools on the ends of the said cross-shaft and placed about the pulleys on the supporting frame and the vertical post and the ends secured to the frame F , a worm-wheel secured on the cross-shaft, and a worm and a shaft by which the shaft E may be rotated 85 to either raise or lower the frame F and the front end of the stacker, substantially as described, and for the purpose set forth.

3. The combination, with the frame F , actuating-shaft J , gear-wheels $d^8 f^2$, vertical shaft 95 K , having gear-wheels $f^8 f^9$ loosely mounted thereon, having inwardly-projecting clutch-teeth, as $g' g^2$, a sliding clutch to engage therewith, gear-wheels $f^3 f^4$, shaft O , sprocket-wheels P and m^7 , chain n^9 , wheel g , shaft Q , 100 worm h^7 , worm-wheel h^8 , shaft R , pinion k , segment T , ring k^8 , having perforations k^9 , pins p , and a gear-shipper, these parts operating jointly, as shown and described, to continuously rotate the endless apron and to 105 oscillate the carrier-frame about its pivotal connection with the supporting-frame, substantially as set forth.

4. The combination, with a stacker-supporting frame, of a cross-shaft, E , extending 110 through said frame, having on its outer ends spools having a toothed connection with collars b , rigidly secured to said shaft, and having teeth on their outer face to engage similar teeth on the inner face of said spool, and 115 a nut by which said spool may be held in engagement with the said collar or released therefrom, substantially as described.

5. The combination, with a supporting-frame and a depending frame, X , of a cross-shaft, E , extending through said frame, supported in journal-boxes, as a^5 , a folding frame, F , supported on the inner ends of said journal-boxes, collars b , rigidly secured to 120 said shaft, spools a^9 , loosely mounted upon the ends of said shaft and adapted to be fixed to and turn in unison with the collars b , cables connecting said spools with the frame F , a spool, a^8 , mounted on shaft E , a hoisting-rope, n^6 , secured to said spool and to free end of 125 lever W , a worm-wheel, b^2 , mounted on shaft E , a worm, b^5 , and crank-shaft b^4 , whereby the shaft E may be rotated, the frame F raised to a vertical position, the lever W drawn

down, and the stacker raised, substantially as set forth.

6. The combination, in a straw-stacker, of a supporting-frame having side sills, as D, a cross-shaft, E, supported on said sills and having collars b rigidly mounted thereon, said collars adapted for fixed engagement with spools a⁹, loosely mounted on said shaft, cables adapted to wind on and off said spools, 10 the ends of said cables secured to a folding frame, F, a worm-wheel, b², a worm, b⁵, and a shaft, b⁴, to actuate said worm, substantially as described, and for the purpose set forth.

7. In an oscillating straw-stacker, a supporting-frame, F, circular way M, bolster L, pivotally secured thereto, a table, N, secured to said bolster and resting on said way, a segment, T, a gear-trip, h², and an adjustable stop operated by the oscillations of said table 20 N to oscillate said gear-trip to change the direction of oscillation of the stacker-frame, substantially as described.

8. The combination of the shaft Q, hanger h⁵, journal-box h⁴, pivotally secured in said hanger, a worm-wheel, h⁸, worm h⁷, a sliding journal-box, h⁶, and a gear-shipping lever, S, whereby said shaft may be oscillated to engage and disengage the said worm with the wheel, substantially as described, and for the 25 purpose set forth.

9. The combination of a gear-shaft mounted

in movable journals and having mounted thereon a gear to engage a co-operative gear, a gear-shipping lever, and a flexible connection extending from said lever to the operator on the stack, whereby the gears may be engaged or disengaged to start or stop the oscillatory movement of the stacker-frame, substantially as described, and for the purpose set forth.

10. The combination of a stacker-frame, as Z, pivotally secured to a supporting-frame, as F, of a lever, W, the rear end of which is secured to the said frame, the front portion resting on a bearing that coincides with the pivotal connection of the frame Z, the front end projected forwardly and downwardly, and a flexible connection with a winding-spool, whereby the rear portion of the stacker-frame Z may be raised or lowered, substantially as described, and for the purpose set forth.

11. The combination of the circular way M, turn-table N, loop h⁴, shoe h⁵, and thumb-screw h⁶, substantially as described, and for the purpose set forth.

In testimony whereof I have hereunto set my hand this 23d day of May, A. D. 1888.

ALLEN A. RUSSELL.
